JOHN F. TWIGG, OF SAN FRANCISCO, CALIFORNIA.

SELF-STARTING AND REVERSIBLE INTERNAL-COMBUSTION ENGINE.

1,136,381.

Specification of Letters Patent. Patented Apr. 20, 1915.

Application filed May 19, 1913. Serial No. 768,421.

To all whom it may concern:

Be it known that I, JOHN F. TWIGG, a citizen of the United States, residing in the city and county of San Francisco and State of California, have invented new and useful Improvements in Self-Starting and Reversible Internal-Combustion Engines, of which the following is a specification.

My invention relates to internal combustion engines and particularly to engines of the two-cycle or two-stroke type having means to start, stop and reverse the engine motion instantly.

This invention has for its object the provision of means for speedily starting, stopping, slowing down, and reversing the motion of the engine with a single lever or handle, and, in fact, control all of the main operating features of the engine by this one means; and to provide an engine with novel and effective features as well as being economical to operate.

Inasmuch as the speed of engines of different characters, such as automobile and marine engines, is required to vary, and the direction of the vehicle or boat reversed, it is necessary to reverse the engine or its propelling shaft. This is usually accomplished by the aid of reversing gears or other mechanism which reverse the propelling shaft, the engine running in one direction only. The speed is regulated generally by reducing the amount of fuel going into the cylinders by throttling the explosive mixture. In some cases the engine is started and reversed directly by compressed air.

My purpose is to produce an engine that can be readily started, slowed down, and stopped, and its motion reversed directly without the above means, but by means of reversing and controlling the action of the delivery of the combustible mixture; also its quantity, and by reversing and controlling the action of the ignition system and timing of the spark. This is done by the movement of a single lever or handle and the speed of the engine increased or decreased without throttling the mixture by the same lever and movement. This same lever also serves as a switch to the ignition system and breaks the electric circuit when placed in stopping position.

The invention consists of the parts and the construction and combination of parts as hereinafter more fully described and claimed, having reference to the accompanying drawings, in which—

Figure 1 is a central vertical semi-section through the engine. Fig. 2 is a sectional plan showing the parts pertaining to the ignition system. Fig. 3 is a vertical section through the mixture pump, showing its construction and the reversing mechanism of the same. Fig. 4 is a diagrammatic view of the pump and engine cycles.

In the present embodiment of my invention I employ a suitably designed pair of cylinders A and A' which are cast together with a sleeve 2 for a piston-rod 3 of a pump piston 4 to slide in, the same being central between cylinders A and A'. An exhaust chamber 5 is formed between the cylinders A and A' and is of large capacity to receive freely the exhaust gases; the chamber being made large by reason of the separation of the cylinders. The cylinder walls are provided with exhaust ports 6 which have a large area, and a water jacket 7 extends entirely around the walls of the cylinders and exhaust chamber. There is a suitable base or crank chamber 8 with stanchions 9 connecting the base to the cylinders.

Superposed upon the cylinders A is a spider-shaped head 10, which carries inlet valves 11 for the cylinders, and of which a pump cylinder 12 and a mixture receiver 13 are parts. A pump head 14 extends over the receiving chambers 13 and carries a relief valve 15 for each. The pump 12 is fitted with superposed inlet valves 16 and delivery valves 17 and 17^a. The delivery valve 17 leads to the cylinder A and valve 17^a leads to cylinder A'.

The cylinders A—A' are fitted with pistons 18 which are connected to a crank-shaft 19 by connecting rods 20. The pump piston-rod 3 is connected to parallel joined rockers 21 by a pin and sliding boxes 22 which are slidable in channels 23 of the rockers 21, which rockers are provided with a pin 24 which receives supporting arms 25, about which rocker 21 tilts. The supporting arms 25 hinge on the crank shaft 19 and through them the position of the rockers 21

is controlled by a hand-lever 26, connected to a crank 26' on a rocker-shaft 26^a, having cranks 26^b joined to connecting rods 27 which are connected at 27' to the fulcrum 5 arms 25.

A lever 28 is provided for operating or revolving a variable electric contact point 29 of a timer on the crank-shaft, which timer consists also of contact points 29^a and 29^b. That part of the timer which contains the points 29^a and 29^b is fixed to the crank-shaft 19; the two points being approximately 180° apart and each on a line with its respective crank and insulated from the engine shaft and the cranks also being 180° apart. That part of the timer which contains the point 29 is also insulated from and is revolved on the shaft 19 by the lever 28 through a segmental gear 30 and a train 10 of gears 30', one of which is on an inner shaft 31. By moving the lever 28 the full length of a fixed quadrant 34, the point 29 is revolved around the shaft 19 about 30° more than a complete turn, or about 15° on 15 either side of the top center. This fifteen degrees is to allow for advancing the spark before the top center, when running at high speed. When starting the engine the point 29 is moved against the direction of the 20 crank movement and when stopping the engine it is moved in the same direction as the crank.

Electric contact is made from point 29^b through a commutator brush 29^c to a spark 25 plug 32 of cylinder A' through an induction coil, and in the same way a connection from the spark plug in cylinder A to point 29^a through commutator 29^d is made. A wire is connected at insulated plates 33, which are 30 insulated from a quadrant 34, and circuit is made only when the lever 28 comes into contact with the plates 33 through a suitable 35 electric battery or magneto, and when the lever 28 is moved toward the center of the quadrant and off the plates 33, the electric current is cut off.

For the purpose of operating the lever 28 simultaneously with the lever 26, screws 35, which are adjustable in the lever 26, are 40 provided to engage and move the lever 28 in unison and with lever 26, or the screws may be set so that lever 28 will lag behind lever 26 in either direction that it is moved. Hence, when the pump lever 26 is moved to 45 its limit, a retarded or late spark will be generated in the cylinders. If an advanced spark is required, lever 28 is independently moved farther toward the end of quadrant 34.

50 The area of the pump piston 4 is double the area of the power pistons 18, so to pump the full charge of the working stroke of the pistons only half the stroke of the power piston is used in the pump. Hence the 55 stroke of the rod 3 by an eccentric 37 is one-

half of crank 19. The pump is double acting; the top side pumping for the forward cylinder A and the bottom side pumping for the after cylinder A'. The eccentric 37 operates the piston 4 through an eccentric 70 strap and yoke 38, joined at 38' to the rockers 21, which engage the piston-rod 3.

The rockers 21 swing from one side of the shaft to the other by the lever 26, thereby reversing the action of the pump piston 4. 75 The pump eccentric is placed approximately at 135° in advance of the following crank; hence when exhaust ports 6 are open wide the pump piston 4 is at about its highest velocity and is replenishing its respective receiver 13, and as the pump piston reaches the end of the stroke exhaust ports 6 are covered by the working pistons 18 about the same time. It will be seen that by moving the rocker 21 to the opposite side, the other end of rocker 21 operates the pump and its action is reversed; the charge being delivered for the opposite running of the engine. It will also be seen that if rocker 21 is placed centrally there will be no stroke to pump, as 80 indicated by the dotted lines 40, and between the ends and middle of the segmental rocker 21 the stroke of the pump may be 85 varied and the speed and power of the engine governed thereby. 95

The inlet valves 11 are opened by the pressure of gas in the receiving chambers 13 and the desired pressure therein is maintained by more or less tension on springs 36 which close the valves 11. The relief valves 15 also 100 may be set to the maximum pressure desired in the chamber 13, and in case of an explosion in the chamber will relieve the parts from unnecessary strains or stresses by automatically opening. A branched inlet pipe 105 39 is provided for connecting a carburetor to the pump 12.

It will be seen that, as the cranks are 180° apart, when the engine is at rest the normal position of the cranks would be 90° and 270° 110 respectively and the pistons at about the middle of the stroke. This is because of the pressure in the cylinders and it being the angle of equal resistance or balancing point, so that when the engine stops the cranks 115 will generally be at this point with little variation. At this point the pump eccentric 37 would be at about 45° off the top center, thereupon by moving the rocker 21 from right to left it would give the pump about 120 70% of its stroke, and by working the lever 26 forward and back, gas or mixture would be pumped into the receiver 13. When sufficient pressure was reached the valve 11 125 would open and the cylinders be filled.

The operation of the engine is as follows: With a suitable carburetor and fuel at the inlet pipe 39, and with the suitable spark plugs at 32 and a suitable battery and spark coil connected through the timer 29, the en- 130

gine is now ready to operate. We will assume that there is no gaseous mixture in the engine to start with. Lever 26 is taken in hand, which lever stands at the middle of the quadrant when the engine is idle, and lever 28 is in the same position with the screws 35 set so that when lever 26 is moved either forward or back it will draw the lever 28 slightly behind it. Lever 26 is now moved back and forward, and by this action the combustible mixture is drawn from the carburetor at inlet 39 through the valves 16 alternately and delivered through the valves 17 to the receivers 13 alternately, and when pressure in the chambers 13 overcomes the tension of a spring 36 on a valve 11, the valve will open and gas will be forced into the cylinders.

It will be noted that at each stroke of the lever when point 29 passes points 29^a or 29^b a spark is generated in respective cylinders, and when sufficient gas is forced into the cylinder it will ignite and a power stroke will result, turning the engine in the direction that lever 26 indicates to be followed by the successive power strokes. The engine is now running with a retarded or late spark and if more power or speed is desired, lever 28 is taken in hand and moved independently and in advance of lever 26 until the desired point is reached. Should less power and less fuel be wanted, lever 26 is moved toward the middle of quadrant 34 until the engine reaches the speed desired. When it is desired to stop the engine, lever 26 is moved toward the middle of quadrant 34 or until the lever 28 leaves the insulated plate 33. This action both reduces the stroke of the pump cutting down fuel and breaks the electric circuit and shuts off the current. The receiver 13 is now filled with gas and the cylinders also, and if it is desired to run the engine in the opposite direction, lever 26 is moved quickly in the reverse direction and the engine will start. Should it not start, by giving one or two strokes of lever 26 this recharges and at the same stroke ignites it and starts the engine. For more or less power, the same action is taken as in the forward operation. At this time it will be noted that the inlet valve 11 is of large diameter being slightly larger than the cylinder bore and a recess 41 worked around the top of the cylinder into which the valve suspends. When the valve opens, the effect of this recess is to cause the gases to come from the receiver 13 into the cylinder all around and under the bottom of the valve, thereby tending to keep the underside of the valve cool and at the same time creating a body or intact volume of gas moving in a solid unbroken mass toward the bottom of the cylinder. The advantage claimed for this is that there is much less liability of the incoming charge

to mix with the remains of the burnt gases and also lessening the liability of any of the new charge passing through the exhaust ports.

By slight changes in the mechanism the eccentric 37 may be substituted by a crank. The supporting arms 25 might be eliminated by placing another eccentric at the opposite end of the rocker 21 and placed at 90° from the present eccentric with approximately the same results. The elements of the timer 29, 29^a, 29^b, 29^c and 29^d may be combined in one integral device. The receiver 13 is designed to hold approximately one full charge of explosive mixture, and by the large area of valve 11 gives exceptionally quick supply to working cylinders with little resistance to gases.

Having thus described my invention, what I claim and desire to secure by Letters Patent is—

1. An internal combustion engine comprising separated twin cylinders, with a fuel pump arranged above and overlapping the cylinders, said pump comprising a piston and its rod, and a guide for the piston-rod located between the cylinders.

2. An internal combustion engine comprising separated twin cylinders, with a fuel pump arranged above and overlapping the cylinders, said pump comprising a piston and its rod, and a guide for the piston-rod located between the cylinders, automatic inlet valves for the cylinders, and receiving chambers interposed between said cylinders and the pump.

3. In an internal combustion engine comprising separated twin cylinders, with a fuel pump arranged intermediately thereof, said pump comprising a piston and its rod, a guide for the piston-rod located between the cylinders, automatic inlet valves for the cylinders, receiving chambers interposed between said cylinders and the pump, and safety valves for the receiving chambers.

4. An internal combustion engine comprising separated parallel cylinders, pistons reciprocatable in said cylinders, a crank-shaft to which the pistons are connected, a manifold for the supply of fuel, a double-acting pump deriving fuel from said manifold, receiving chambers interposed between said pump and the engine cylinders, automatic inlet valves controlling the passage of gas from said chambers to the cylinders, and a manually operable mechanism for reciprocating the pump piston for the supply of gas to said receiving chambers.

5. An internal combustion engine comprising separated parallel cylinders, pistons reciprocatable in said cylinders, a crank-shaft to which the pistons are connected, a manifold for the supply of fuel, a double-acting pump deriving fuel from said manifold, receiving chambers interposed be-

- between said pump and the engine cylinders, automatic inlet valves controlling the passage of gas from said chambers to the cylinders, and a manually operable mechanism 5 including a lever for reciprocating the pump piston for the supply of gas to said receiving chambers, said mechanism comprising a connection between said lever and the pump whereby the volume of the fuel forced by the 10 pump into the receiving chambers may be varied.
6. An internal combustion engine comprising separated parallel cylinders, pistons reciprocatable in said cylinders, a 15 crank-shaft to which the pistons are connected, a manifold for the supply of fuel, a double-acting pump deriving fuel from said manifold, receiving chambers interposed between said pump and the engine 20 cylinders, automatic inlet valves controlling the passage of gas from said chambers to the cylinders, a manually operable mechanism for reciprocating the pump piston for the supply of gas to said receiving chambers, 25 said mechanism comprising a lever and connections with said lever and the pump whereby the volume of the fuel forced by the pump into the receiving chambers may be varied; and an ignition system co-operative with and by said lever for the ignition 30 of gases forced into the engine cylinders by said pump.
7. In an internal combustion engine, a plurality of combustion cylinders, a pump 35 for supplying a combustible mixture to said cylinders, and a manually adjustable mechanism having means for varying and reversing the stroke of the pump to change the volume of combustible mixture forced thereby into the combustion cylinders, and to reverse the direction of the revolution of the engine.
8. In an internal combustion engine, a plurality of combustion cylinders, a pump 45 for supplying a combustible mixture to said cylinders, and a manually adjustable mechanism for varying the stroke of the pump to change the volume of combustible mixture forced thereby into the combustion cylinders, said mechanism comprising a tilttable 50 lever or rocker connected to the pump piston-rod, and an adjustable fulcrum for said rocker whereby the range of operation of the rocker may be varied.
- 55 9. An internal combustion engine comprising a plurality of combustion cylinders having exhaust ports, automatic inlet valves for the cylinders, pistons operable in said cylinders, a pump common to the cylinders 60 for supplying a compressed fuel charge thereto, said pump including a piston and its rod, a guide on the cylinders for the piston-rod, a crank-shaft to which the pistons of the engine are connected, and means con-
- nnecting the piston-rod and the crank-shaft 65 whereby the pump will be operated by the power of the engine or may be operated by hand.
10. An internal combustion engine comprising a plurality of combustion cylinders 70 having exhaust ports, automatic inlet valves for the cylinders, pistons operable in said cylinders, a pump common to the cylinders for supplying a compressed fuel charge thereto, said pump including a piston and 75 its rod, a guide on the cylinders for the piston-rod, a crank-shaft to which the pistons of the engine are connected, means connecting the piston-rod and the crank-shaft whereby the pump will be operated by the 80 power of the engine, and a manually controlled mechanism for varying the stroke of the pump.
11. An internal combustion engine comprising a plurality of combustion cylinders 85 having exhaust ports, automatic inlet valves for the cylinders, pistons operable in said cylinders, a pump common to the cylinders for supplying a compressed fuel charge thereto, said pump including a piston and 90 its rod, a guide on the cylinders for the piston-rod, a crank-shaft to which the pistons of the engine are connected, means connecting the piston-rod and the crank-shaft whereby the pump will be operated by the 95 power of the engine, and a manually controlled mechanism for changing the stroke of the pump to deliver variable quantities of fuel to the engine and thereby control its speed. 100
12. An internal combustion engine comprising a plurality of combustion cylinders having exhaust ports, automatic inlet valves for the cylinders, pistons operable in said cylinders, a pump common to the cylinders 105 for supplying a compressed fuel charge thereto, said pump including a piston and its rod, a guide on the cylinders for the piston-rod, a crank-shaft to which the pistons of the engine are connected, means connecting the piston-rod and the crank-shaft whereby the pump will be operated by the power of the engine, a manually controlled mechanism for changing the stroke of the 110 pump to deliver variable quantities of fuel to the engine and thereby control its speed, said mechanism comprising a rocker, an adjustable fulcrum for said rocker, means for adjusting the fulcrum, said rocker being connected to the piston-rod, and a connection between the rocker and the crank-shaft. 115
13. A self-starting internal combustion engine comprising a plurality of engine cylinders, pistons reciprocatable therein, a crank-shaft to which the pistons are connected, automatic inlet valves for the cylinders, exhaust ports in the cylinders for the relief of burnt gas, a double-acting 120
- 125

5 pump for supplying fuel from a suitable source to said cylinders under sufficient pressure to ignite, an ignition system for igniting the compressed gases, and means for reversing the pump to change the direction of rotation of the engine.

14. A self-starting internal combustion engine comprising a plurality of engine cylinders, pistons reciprocatable therein, a 10 crank-shaft to which the pistons are connected, automatic inlet valves for the cylinders, exhaust ports in the cylinders for the relief of burnt gas, a double-acting pump for supplying fuel from a suitable source to 15 said cylinders under sufficient pressure to ignite, an ignition system for igniting the compressed gases, and means for reversing the pump to change the direction of rotation of the engine, said means comprising a 20 rocker, an adjustable fulcrum for the rocker, and connections between the piston of the pump and the rocker and between the crank-shaft of the engine and the rocker whereby the pump may be operated by the power of 25 the engine or manually operated.

15. A self-starting internal combustion engine comprising a plurality of engine cylinders, pistons reciprocatable therein, a crank-shaft to which the pistons are connected, automatic inlet valves for the cylinders, exhaust ports in the cylinders for the relief of burnt gas, a double-acting pump for supplying fuel from a suitable source to 30 said cylinders under sufficient pressure to ignite, an ignition system for igniting the compressed gases, means for reversing the pump to change the direction of rotation of the engine, said means comprising a rocker, an adjustable fulcrum for the rocker, and 35 connections between the piston of the pump and the rocker and between the crank-shaft of the engine and the rocker whereby the pump may be operated by the power of the engine, and a manually operable device for 40 operating the rocker to reciprocate the piston of the pump when the engine is idle for the forcing of a combustible fuel to the engine cylinders.

16. A reversible internal combustion engine comprising a plurality of cylinders, a 50 double-acting pump for compressing a charge of combustible fuel in said cylinders, pistons operable in the cylinders, a crank-shaft connected to the pistons, automatic inlet valves opened by compressed fuel from the pump, and a means for reversing the pump and for changing its stroke.

17. A reversible internal combustion engine comprising a plurality of cylinders, a 60 double-acting pump for compressing a charge of combustible fuel in said cylinders, pistons operable in the cylinders, a crank-shaft connected to the pistons, automatic inlet valves opened by compressed fuel from

the pump, and a manually operable means 65 for operating the pump to create an initial pressure in the engine cylinders, while the engine is idle, and for reversing the stroke of the pump to change the direction of rotation of the engine.

70

18. An internal combustion engine comprising a plurality of combustion cylinders, pistons reciprocatable therein, a crank-shaft connected to said pistons, a sparking system comprising a commutator secured on the 75 shaft and having contact points coördinately positioned with relation to respective cranks of the shaft, a timer having a contact point, said timer point being turnably mounted relative to and upon the shaft, 80 spark plugs in the cylinders of the engine having respective connections with the commutator, a quadrant provided with insulated contact plates on each side of its central portion, connections between said contact 85 plates with the electric system, a manually controlled lever for revolving the turnable timer about the shaft to control the spark, and a device carried by said lever for closing the circuit through one or the other of 90 the contact plates of the quadrant to control the sparking of the plugs in the cylinders of the engine according to the required direction of rotation of the crank-shaft.

19. An internal combustion engine comprising a plurality of combustion cylinders, pistons reciprocatable therein, a crank-shaft connected to said pistons, a sparking system comprising a commutator secured on the shaft and having contact points coördinately 95 positioned with relation to respective cranks of the shaft, a timer having a contact point, said timer point being turnably mounted relative to and upon the shaft, spark plugs in the cylinders of the engine having respective 100 connections with the commutator, a quadrant provided with insulated contact plates on each side of its central portion, connections between said contact plates with the electric system, a manually controlled lever for revolving the turnable timer about 105 the shaft to control the spark, a device carried by said lever for closing the circuit through one or the other of the contact plates of the quadrant to control the sparking of the plugs in the cylinders of the engine according to the required direction of 110 rotation of the crank-shaft, and a reversible pump for charging said cylinders, said pump being connected to the operating lever 115 controlling and reversing the sparking of the spark plugs.

20. The combination in an internal combustion engine having combustion cylinders, pistons reciprocatable therein, and a crank-shaft, of a pump for charging the cylinders with a compressed combustible fuel, an ignition system for producing an electric spark

in the cylinders for the ignition of the fuel, and a manually controlled means for simultaneously operating the pump to charge the cylinders and timing the energization of the electric system of the spark plugs.

21. In an internal combustion engine having a crank-shaft, pistons connected thereto, and cylinders therefor, the combination of a pump for charging the cylinders with a combustible vapor, said pump being reversible for controlling the direction of rotation of the crank-shaft of the engine, an ignition system including spark plugs in the cylinders of the engine, a commutator ring fast on the shaft of the engine, a timer movably mounted upon the shaft, independent contact plates, and a hand lever for operating, reversing, and changing the stroke of the pump and carrying a contact member for completing the ignition circuit through either of said contact plates.

22. In an internal combustion engine having a crank-shaft, pistons connected thereto, and cylinders therefor, the combination of a pump for charging the cylinders with a combustible vapor, said pump being reversible for controlling the direction of rotation of the crank-shaft of the engine, an ignition system including spark plugs in the cylinders of the engine, a commutator ring fast on the shaft of the engine, a timer movably mounted upon the shaft, independent contact plates, and a hand lever for operating, reversing and changing the stroke of the pump and carrying a contact member for completing the ignition circuit through either of said contact plates, said contact member having a limited variable lost motion with respect to said lever for controlling the timing of the spark with relation to the position of the pistons.

23. In an internal combustion engine having a crank-shaft, pistons connected thereto, and cylinders therefor, the combination of a pump for charging the cylinders with a combustible vapor, said pump being reversible for controlling the direction of rotation of the crank-shaft of the engine, an ignition system including spark plugs in the cylinders of the engine, a commutator ring fast on the shaft of the engine, a timer movably mounted upon the shaft, independent contact plates, and a hand lever for operating, reversing and changing the stroke of the pump and carrying a contact member for completing the ignition circuit through either of said contact plates, said contact member having a limited variable lost motion with respect to said lever for controlling the timing of the spark with relation to the position of the pistons, and said contact member having connections with and for operating the timer ring on the crank-shaft.

24. In an internal combustion engine having combustion cylinders, pistons recipro-

catable therein, and a crank-shaft connected to the pistons, the combination of a reversible pump for compressing a fuel charge in the combustion cylinders, said pump having a piston and its rod, means connecting the piston-rod to the crank-shaft for reversing the pump and for changing its stroke, said means including a manually movable lever, an ignition system for the engine including spark plugs in the engine cylinders, a timer ring movable relative to and mounted on the crank-shaft, contact plates in the electric circuit, and means controlled by said hand lever for changing the position of the timer ring simultaneously with the operation of the pump connection.

25. In an internal combustion engine having combustion cylinders, pistons reciprocable therein, and a crank-shaft connected to the pistons, the combination of a reversible pump for delivering a fuel charge in the combustion cylinders, said pump having a piston and its rod, means connecting the piston-rod to the crank-shaft for reversing the pump and for changing its stroke, said means including a manually movable lever, an ignition system for the engine including spark plugs in the engine cylinders, a timer ring movable relative to and mounted on the crank-shaft, contact plates in the electric circuit, and means controlled by said hand lever for changing the position of the timer ring simultaneously with the operation of the pump connection, said lever automatically interrupting the ignition circuit when the engine is stopped by the adjustment of said pump-actuating means to the neutral position.

26. In an internal combustion engine having combustion cylinders, pistons reciprocable therein, and a crank-shaft connected to the pistons, the combination of a reversible pump for compressing a fuel charge in the combustion cylinders, said pump having a piston and its rod, means connecting the piston-rod to the crank-shaft for reversing the pump and for changing its stroke, said means including a manually movable lever, an ignition system for the engine including spark plugs in the engine cylinders, a timer ring movable relative to and mounted on the crank-shaft, contact plates in the electric circuit, and means controlled by said hand lever for changing the position of the timer ring simultaneously with the operation of the pump connection, said lever automatically interrupting the ignition circuit when the engine is stopped by the adjustment of said pump-actuating means to the neutral position, and whereby the position of the timer ring is reversed when the direction of rotation of the engine is to be reversed.

27. A starting and reversing mechanism for internal combustion engines comprising

- in combination with the cylinders of the engine, a reversible pump for charging the cylinders of the engine with a combustible vapor, a crank-shaft in the engine, a connection between the piston of the pump and said crank-shaft, said connection including an eccentric with a predetermined relation to the cranks of the crank-shaft, and said connection including a manually controlled reversing rocker for changing the position of the pump piston with relation to the cranks of the crank-shaft.
28. In an internal combustion engine, an engine-operated, combustible mixture pump for charging the engine cylinder, a manually operable means connected to the pump for varying its stroke, and a device for simultaneously changing the time of the spark operated by and in one action with said means.
29. In an internal combustion engine, an engine-operated, combustible mixture feed pump, manually operable means connected to the pump for reversing and varying its stroke, and a device simultaneously operable in one action with said means for controlling the ignition of the engine.
30. In an internal combustion engine with its sparking system, an engine-operable, combustible mixture pump for charging the engine, and a means for manually reversing or for varying the stroke of said pump, for controlling the time of sparking the engine, and for cutting in or cutting out the sparking circuit all in one action of the means.
31. In an internal combustion engine with its sparking system, a pump for charging the engine with a combustible mixture, a mechanism for driving the pump by engine power, a means for reversing or for varying the pump stroke, an instrumentality for timing the spark, a circuit member for cutting in or out said system, and a single controller for operating said member, said instrumentality, means and mechanism at a single action.
32. In an internal combustion engine, an ignition system with a contact member, a spark timer for the system, a lever for controlling the timer, and a movable contact member controlled by said lever whereby a circuit is completed at said member when the lever is thrown one way and broken when reversed.
33. An internal combustion engine having an inlet port and an automatic valve closable thereover, and an annular recess about the port for directing the incoming fuel mixture across and below the valve into a compact volume, said valve being of a diameter substantially equal to that of the cylinder of the engine.
34. An internal combustion engine having an inlet port and an automatic valve closable thereover, an annular recess about the port for directing the incoming fuel mixture across and below the valve into a compact volume, said valve being of a diameter substantially equal to that of the cylinder of the engine, and a receiving chamber on the engine between which and the cylinder the valve is interposed.
35. An internal combustion engine comprising a plurality of cylinders, a double-acting pump for compressing a charge of combustible fuel in said cylinders, pistons operable in the cylinders, a crank-shaft connected to the pistons, automatic inlet valves opened by compressed fuel from the pump, and a manually or engine operable means for operating the pump to create an initial pressure in the engine cylinders, while the engine is idle, and for reversing the stroke of the pump to change the direction of rotation of the engine.
36. In combination with a cylinder and its piston, a shaft, a rocking quadrant having a sliding connection to the piston for changing its stroke, a fulcrum arm upon which the quadrant is mounted in the plane approximate its central radius, and means for oscillating the quadrant on its fulcrum.
37. In combination with a cylinder and its piston, a shaft, a rocking quadrant having a sliding connection to the piston for changing its stroke, a fulcrum arm upon which the quadrant is mounted in the plane approximate its central radius, means for oscillating the quadrant on its fulcrum, said arm being on and adjustable about the shaft, and means for controlling the arm.

In testimony whereof I have hereunto set my hand in the presence of two subscribing witnesses.

JOHN F. TWIGG.
